UNITED STATES PATENT OFFICE.

A. LIVINGSTON BOGART, OF JAMAICA, NEW YORK, ASSIGNOR TO ABRAHAM L. BOGART, OF SAME PLACE.

ELECTRIC GAS-LIGHTING ATTACHMENT FOR BURGLAR-ALARMS.

SPECIFICATION forming part of Letters Patent No. 292,786, dated February 5, 1884.

Application filed July 17, 1883. (No model.)

To all whom it may concern:

Be it known that I, A. LIVINGSTON BOGART, of Jamaica, in the county of Queens and State of New York, have invented an Improved 5 Electric Gas-Lighting Attachment for Burglar-Alarms; and I hereby declare the following to be a full, clear, and exact description thereof, reference being had to the accompanying drawings, which form a part of this specification.

This invention relates to an improvement in apparatus to be used in connection with burglar-alarms for the purpose of automatically turning on and igniting one or more gas-jets whenever the burglar-alarm bell is sounded or the indicator-drop falls; but it may also be employed for other analogous purposes. In the several apparatus heretofore used for this purpose the usual method has been to put 15 the burner and the burglar-alarm in multiple arc from the same battery, so that the closing of the circuit at a door or a window would operate both the burner or burners and the burglar-alarm simultaneously; or the indicator-drop in falling would shunt part of the 20 current through the burner to be lighted; or in another form of apparatus the indicator-drop in falling would throw an independent battery upon the burner-circuit. In either of 25 the first-mentioned cases—that is, where a single battery is employed for the two purposes—there is always a possibility of the current being so weakened by the division that either the burglar-alarm or the burner will 30 fail to operate at all, or will operate imperfectly—as, for instance, the gas may be partially turned on but not ignited; and in the last mentioned case—that is, where two batteries are employed—there is danger that in 35 the excitement and confusion the burner-battery may be left on the burner and thus exhaust itself; but by means of my improvement these several difficulties are overcome 40 and a separate circuit is formed for the burglar-alarm, and each burner to be lighted, so that the circuits are not weakened by dividing them, and the burners, after having been 45 successively lighted, are automatically cut out of circuit. In my said invention either one

or two batteries may be used, as will be presently explained and described.

The invention consists of an automatic apparatus, the main feature of which is that when set with its magnet in a burglar-alarm circuit it will, when said circuit is closed at a 55 door or a window, first permit the indicator-drop to fall, then open the burglar-alarm circuit and switch the battery successively to one or more gas-burners to light the same, and then again throw the current upon the burglar-alarm circuit to sound a continuous alarm; or, as a modification thereof, will, when the burglar-alarm circuit is closed, first throw a 60 special battery successively into and out of circuit with one or more burners and then 65 cut itself out of the burglar-alarm circuit; and it further consists in certain novel constructions and combinations of parts, as hereinafter particularly set forth.

In the accompanying drawings, Figure 1 70 represents my improved apparatus as operated by one battery only, and Fig. 2 represents the same as used in connection with two batteries.

Similar letters of reference indicate the same 75 parts in both of said figures.

A' may represent any suitable support to which my improved apparatus is attached, and E the frame of a clock-work, by which the mechanism hereinafter described is driven. 80

A is a lever affixed to the shaft C of the clock-work.

Upon the shaft C is secured a ratchet-wheel, B, having two or more teeth, and upon said shaft is also secured a coiled spring, D, one 85 end of which is secured to said shaft and its other end to the frame E. A toothed wheel, F, is fitted loosely upon said shaft C, and provided with a pawl, G, which engages with the ratchet-wheel B, and provided also with pins 90 H, equal in number to the number of teeth on the ratchet-wheel B. The wheel F drives a pinion and escape-wheel, I, with its verge J, from which latter is suspended a pendulum, O.

K is an electro-magnet, the armature of 95 which is pivoted at m, and is provided with a stop-pin, N, which, when the armature is in its normal position, (or off the magnet,) en-

gages the pendulum O, and thus prevents the clock-movement from running, and when the armature is attracted to the magnet said pin N is released from the pendulum and the clock-work is started.

- P is a spring, the upper end of which extends upward to engage with the free end of the lever A, and on that part of said spring which is opposite to the end of the armature 10 L is formed a catch, Q, which, when said armature is attracted and the upper end of the spring freed from the lever A, projects over the end of the armature and prevents the pin N from stopping the clock-work until the 15 spring P is again pushed back by the lever A.

S is a spring, against which the lever A abuts when the apparatus is set at "off," and T a similar spring, against which said lever abuts when the apparatus is set at "on."

20 Both these springs are insulated.

The electric connections are as follows: Referring to Fig. 1, U is the battery, from one pole of which a wire is connected in the usual manner with the several door and window 25 springs used in burglar-alarm work, as at V, and from its other pole the wire a is connected to the frame of the clock-work. The burglar-alarm bell d and its indicator are connected by the wire b, first with the insulated spring S, 30 then by wire c with the electro-magnet K, and thence by wire e with the insulated spring T.

1 and 2 are the gas-burners to be lighted, and are of the kind known as "vibrators" or 35 "automatic" gas-burners. Any desired number of these may be used, and they are connected, respectively, by wires f, f, with insulated springs X, Y, each having its separate spring and wire connection. The said springs 40 are placed out of contact with the wheel F, but in such position that when said wheel rotates (in the direction of the arrow) the pins H H will come successively in contact with them; and said springs are bent, so that each 45 will make two or more contacts with the pins as they pass the same to insure the lighting of the burners.

W is a "spark-coil," connected to the ground and to that pole of the battery which is 50 opposite to the one connected to the frame of the clock-work.

In order to indicate more clearly the several circuits, the wires which form the burglar-alarm circuit are shown in full lines, and those 55 which form the burner-circuits are shown by dotted lines.

The operation is as follows: To set the apparatus, the end of the lever A is set to "on," and in contact with the spring T, the ratchet 60 B engaging with the pawl G and holding it, and the upper end of the spring P being now released from the lever A, the catch Q rests against the end of the armature L, as shown. Now, should the burglar-alarm circuit be 65 closed at V, the current will pass from the battery U by wire n, connection V, wire n', indi-

cator-magnet d', bell-magnet d'; thence by wires b and c to magnet K; thence by wire e and spring T, through the lever A and frame of clock-work, to wire a and back to battery U, 70 the result being that the indicator-drop r will fall, the bell d be rung, and the armature L of the magnet K attracted, and thereby the pin N will be withdrawn from the escapement J and the clock-work set in motion by the force 75 of the coiled spring, so that the lever A will begin to move toward the spring S. As soon as the lever moves out of contact with T the circuit is broken and the current cut off from the burglar-alarm and from the magnet K; 80 but the catch Q has in the meantime passed over the end of the armature and prevents the pin N from stopping the clock-work; and hence the lever A continues its movement toward S, and during its onward movement the 85 pin H is brought in contact with the spring X, and the current then flows from the "ground," through the coil W, battery U, wire a', (shown by dotted line,) frame of clock-work, pin H, and spring X, (which make one or more contacts,) and by wire f' to burner 1, and thence to the gas-pipe and ground, lighting said burner. In the further onward movement of lever A, and wheel F the pin H passes out of contact 90 with X and comes in contact with Y, thereby igniting the gas at burner 2, and then passes out of contact with Y. When said lever A, in its continued movement, makes contact with the spring S, the magnet K is shunted out of circuit, the burglar-alarm circuit then being 95 made from wire a, lever A, and spring S to wire b, as before. When the lever A arrives at S, it pushes back the upper end of the spring P and withdraws the catch Q from the armature L, which latter is then retracted by the 100 spring t, when the pin N again stops the clock-work by coming in contact with the pendulum O; but the burglar-alarm circuit being still closed, either through the closed connection at V or through the shunt closed by the falling 105 of the indicator-drop, the bell will continue to ring until both these connections are broken.

I do not confine myself to the exact forms of mechanism herein shown and described, as it is obvious that the same may be modified or 110 changed without departing from the principles of my invention, the object being to construct the same so that when the burglar-alarm circuit is closed at a door or window and the first alarm sounded it will operate automatically 115 to first cut off the burglar-alarm circuit, then switch the battery successively to the several gas-burners to ignite the same, cutting out each burner as soon as lighted, and then again throw the current upon the burglar-alarm circuit to 120 sound a continuous alarm, so that no two circuits shall be closed at the same time.

In the modification shown in Fig. 2 no change is made in the construction of the apparatus, except that the end of the lever A is covered 125 with insulating material and the springs S and T are brought together, but not in contact with

each other until brought into contact by the lever A on its arriving at "off," as will be presently described. In this case, as in the former, the lever A, being set at "on," is retained in that position by the ratchet and pawl, and the catch Q rests against the end of the armature L. The burglar-alarm circuit is from one pole of the battery U, the wire n, connection V, wire n', to the alarm-instrument; thence by wire b, spring S, and wire c to magnet K; thence by wire e and lever A through frame of clock-work, and by wire a back to the battery U, the lever A being set at "on," and the contact between the springs S and T being broken. When this circuit is closed at V, (the lever A being set at "on,") the armature L is attracted, the catch Q passes over the end of the same, pin N is withdrawn, releasing the clock-work, and the lever A begins to move toward the springs S and T. When the pin H makes contact with the springs X and Y, respectively, a separate battery, U', is turned upon the automatic burners 1 2, the circuit being from the ground through the spark-coil W and battery U'; thence to the frame of the clock-work and pin H; thence through whichever of the springs X Y with which said pin is in contact, by one of the wires f, to the burner attached to said wire to ignite said burner. The burners are thus successively brought into and thrown out of circuit, as in the former case; but the burglar-alarm circuit remains closed meanwhile, either through the connection at V or through the shunt m', closed by the falling of the indicator-drop. When the lever A arrives at S, it brings the latter into contact with T, thus shunting the magnet K out of circuit, and at the same time pushes back the spring P, thereby withdrawing the catch Q and stopping the clock-work, the newly-formed burglar-alarm circuit still remaining closed.

What I claim as my invention is—

1. An electric gas-lighting attachment for burglar-alarms, consisting of an automatic switch, A, constructed as described, and operated by a clock-work mechanism, which is set in motion and stopped by the armature of an electro-magnet, K, in the manner set forth,

and is provided with a series of circuit-closers adapted, as described, to turn the battery-current upon each burner separately to ignite the same, in combination with electrical connections consisting of a separate circuit for each burner, and another separate circuit including an ordinary burglar-alarm instrument, the whole being constructed to operate as described, so that no one of said circuits interferes with the action of any other of said circuits, and each burner is ignited separately, and immediately thereafter is cut out of circuit, as set forth. 50 55 60

2. An electric burglar-alarm and gas-lighting apparatus composed of the following parts in combination—namely, the automatic switch A, constructed and operated by clock-work mechanism, as described, the escapement I, and pendulum O, the armature L, provided with the stop-pin N, a burglar-alarm instrument, the springs S and T, and the burglar-alarm circuit and separate gas-burner circuits, including the circuit-closers H and X Y, the whole constructed and operating, as described, to first sound the alarm, then to divert the current to each burner successively, and then to divert the current again to the burglar-alarm for the purpose of effecting a continuous alarm after the last burner-circuit has been made and broken. 75

3. The combination, with the magnet K and its armature L, lever A, spring D, and train of clock-work, of the catch Q, mounted upon the spring P, as shown and described, for the purpose set forth. 80

4. The burglar-alarm and switch-circuit, composed of the battery U, wire a, clock-work frame E, lever A, spring T, wire e, magnet K, wire c, spring S, and burglar-alarm instrument, as shown and described. 85

5. The combination, as shown and described, of the burglar-alarm circuit, magnet K, gas-lighting circuit, indicated by dotted lines, and the clock-work movement. 90
